UNITED STATES PATENT OFFICE.

HEMBURN M. CHAMBLIN, OF NEWTON, ILLINOIS.

MECHANICAL TELEPHONE.

SPECIFICATION forming part of Letters Patent No. 439,475, dated October 28, 1890.

Application filed May 10, 1890. Serial No. 351,295. (No model.)

To all whom it may concern:

Be it known that I, HEMBURN M. CHAMBLIN, a citizen of the United States, residing at Newton, in the county of Jasper and State of Illinois, have invented certain new and useful Improvements in Mechanical Telephones, of which the following is a specification, reference being had therein to the accompanying drawings, in which—

10 Figure 1 represents a vertical sectional view of a mechanical telephone with my invention applied thereto; Fig. 2, a vertical sectional view of the button enlarged, and Fig. 3 a front view of the same.

15 The object of the invention is to so improve the button connecting the line-wire to the diaphragm that the transmitted sounds will be reproduced more clearly and distinctly, as will more fully hereinafter appear.

20 In the drawings, A designates an ordinary mechanical or acoustic telephone provided with the diaphragm B and mounted in any suitable manner. The line-wire C passes through apertures in the back of the telephone-casing 25 and diaphragm, and is connected to a concavo-convex button D, which it clamps to the center of the front face of the diaphragm. The concave or hollow side of this button is toward the diaphragm, and its circular edge presses

30 upon the face of the same. This button is provided with a suitable number of—say three—openings a, which connect the chamber formed between the hollowed-out side of the button

and the diaphragm with the outside atmosphere.

35 Heretofore these hollow buttons have been imperforated, so as to form a dead-air space between them and the diaphragm, thereby giving to the sound reproduced a muffled effect. It is a fact, demonstrated by experiment 40 and use, that by perforating the button and allowing the air free access to the space behind it all muffling and retardation of the reproductions will be avoided and a clear distinct enunciation produced. Whether my 45 theory be correct or not, experiment has demonstrated the fact that the open button insures a much more efficient operation and clearer enunciation, and counteracts the effect of the wind upon the line-wires more effectually than the solid imperforated button.

50 Having thus fully described my invention, what I claim is—

55 The combination, in a mechanical telephone, of the casing and diaphragm, the line-wire, and a concave button secured to the end of the wire and having its concave side toward the diaphragm, the said button being provided with one or more openings, substantially as described.

60 In testimony whereof I affix my signature in presence of two witnesses.

HEMBURN M. CHAMBLIN.
